UNITED STATES PATENT OFFICE.

WILLIAM T. HARRIS, OF STAUNTON, VIRGINIA.

STEAM-GENERATOR.

1,179,627.

Specification of Letters Patent. Patented Apr. 18, 1916.

Application filed July 21, 1911. Serial No. 639,851.

To all whom it may concern:

Be it known that I, WILLIAM T. HARRIS, a citizen of the United States, residing at Staunton, in the county of Augusta and State of Virginia, have invented certain new and useful Improvements in Steam-Generators, of which the following is a specification.

My said invention consists in various improvements in the construction of steam-boilers especially designed for use on locomotives, whereby substantially perfect combustion is secured and a comparatively high degree of steam pressure thereby generated by a minimum supply of fuel and various other important advantages secured, all as will be hereinafter more fully described and claimed.

Referring to the accompanying drawings which are made a part hereof and on which similar reference characters indicate similar parts, Figure 1 is a longitudinal section through a steam generator of my improved construction applied to a locomotive, Fig. 2 a horizontal section through the same on the dotted line 2—2 in Fig. 1, Fig. 3 a longitudinal vertical section on the dotted line 3—3 in Fig. 2, Fig. 4 a cross section on the dotted line 4—4 in Fig. 1, Fig. 5 a cross section on the dotted line 5—5 in Fig. 1, and Fig. 6 a cross section on the dotted line 6—6 in Fig. 1.

In said drawings the portions marked A represent the outer shell of the generator or boiler, B the combustion chamber and C an inner shell or flue structure leading from the combustion chamber to the smoke-box.

The boiler A may be a locomotive boiler, such as shown, provided with a steam dome 40 a , smoke-box A' and smoke-stack a' , and other ordinary features of construction, or it may be a boiler of any other form. The combustion chamber B is also in the main of any approved form provided with grate bars b , a fuel supply door b' and other common features of construction. It is mounted in the rear end of the boiler A, connected and supported by means of suitable braces and supporting parts.

The flue C comprises a hollow shell preferably rectangular in form with bell-shaped circular ends c and c' provided with flanges which are riveted to a corresponding flange

b^2 , in the front end of the combustion chamber, and a^2 in the front end of the boiler, respectively. By constructing the ends c and c' outwardly flaring, the gases leaving the main combustion chamber are directed into the flue of the inner casing, and at the forward end of this flue (i. e. at the end c') the gases are freely liberated for entrance into the smoke box. This arrangement avoids the baffling effect that would be produced if the ends of the inner flue were square. It will be noted that by reason of this construction the removal of the rivets connecting said flue with said flanges b^2 and a^2 will permit the removal of the entire flue structure C, and all parts thereby, through the front end of the boiler, or, by the cutting of the rivets connecting the front end of flue C with the flange a^2 and the bolts securing the rear end A' of boiler A in position, said flue and combustion chamber may be moved as a body from said boiler. Said flue C is provided with numerous vertical tubes 10 which extend through its top and bottom in transverse rows near each other from one end of said flue to the other, the tubes in the adjacent rows being set staggered in relation to each other. By this means free water circulation is established through said tubes 10 from the lower to the upper part of boiler A and the passage through flue C is obstructed by the vertical tubes so that the heat and other products of combustion are required to take a serpentine course, wrapping around the various vertical tubes in their passage through said flue. The front end of flue C is filled with a series of coils 11 extending vertically and corresponding in arrangement to the tubes 10 but connected in series by suitable couplings both above and below the flue to form a continuous passage through said coils. An inlet pipe 12 is connected with one end of said coils and an outlet pipe 13 with the opposite end. Said inlet pipe 12 is connected by a branch feed pipe 14 with the water tank on the locomotive through which the water is fed from said tank and passes through said coils 11, where it is heated and from which it is discharged through pipe 13 and nozzle 15 into boiler A. A check valve 16 is mounted between nozzle 15 and discharge pipe 13 on

the outside of the boiler which may be removed when required to establish communication with the coil for cleaning purposes. Said flue C is preferably braced with a series 5 of flanged irons c^3 riveted to its sides to afford the required resistance to the exterior pressure.

Within the combustion chamber B I also provide an auxiliary steam generator 20 10 comprising a shell which forms a partition extending transversely of said combustion chamber a distance above the grate bars and preferably inclined from the rear of said combustion chamber downwardly to 15 ward its front end. Said shell is provided with vertical tubes 21 through which the products of combustion may pass from below to above said shell. A water inlet pipe 22 extends from the lower part of boiler A 20 to the front end of said auxiliary boiler 20 and an outlet pipe 23 extends from the rear end of said auxiliary boiler through the end of boiler A, then to a point near the top of said boiler, where it discharges through a 25 nozzle 24, thus establishing a complete circulation through said auxiliary boiler from the lower side of boiler A to its top.

Air supply funnels 25 and 26 are mounted on the sides of the cab with funnel shaped 30 forward ends and their rear ends turned and inserted through suitably formed openings in the rear end of boiler A, thus being arranged to discharge immediately above the rear end of auxiliary boiler 20 in the 35 combustion chamber.

The smoke-stack a' is formed with an inner tube 30 of smaller diameter thus providing an annular space between them. Said 40 annular space terminates in channels 31 and 32 which extend down around the front end of boiler A where they are joined by an L 33 and connected to a rearwardly extending funnel 34 which extends to a point rearwardly beneath the locomotive, for a purpose 45 to be presently described.

In the top of smoke-stack a' is pivoted a valve 35 which is adapted to be operated from the cab by a handle 36 on an operating rod 37 connected by suitable links and levers 50 with the pivot of said valve.

The operation of my said invention is as follows: The products of combustion passing through the vertical flues 21 of the auxiliary generator 20 commingle with the 55 air, coming through funnels 25 and 26, in the combustion chamber above said auxiliary generator and burn freely, filling said combustion chamber with flame of intense heat, which passes through the flue C, being 60 retarded in its progress by the tubes 10 and passing through the serpentine passage ways between said tube, during which passage substantially all of the gases and smoke are consumed. Any cinders or sparks passing

to the smoke-box and up through the smoke-stack strike a deflector 40 located over the inner tube 30 of said smoke-stack and are deflected downwardly through the annular space between said tube 30 and smoke-stack a' into the passages 31 and 32 and are discharged out through the funnel 34. In passing through tunnels, stations and other places where it is desired to confine the gases and smoke as much as possible, the valve 35 may be closed when all of the products of combustion which ordinarily pass through the smoke-stack will be required to take the course above indicated and be discharged from funnel 34. The suction caused by the motion of the train will be sufficient to draw 80 said products of combustion through said funnel. The water coming through pipe 14 is heated in coil 11 and discharged into the boiler through nozzle 15 and from there circulates through the auxiliary generator 85 20, then to the top of boiler A. The water is thus first subjected to a preliminary heating before being introduced into the boiler and then subjected to the intense heat surrounding the auxiliary generator 20 as well 90 as to the heat in the boiler A surrounding flue structure C and its circulation tubes 10. By this means not only is the heating capacity of the structure fully utilized but substantially perfect combustion is secured 95 and all of the heat of the fuel also utilized and thus the greatest degree of steam pressure is generated by the use of the smallest possible amount of fuel.

In addition to the advantages above 100 pointed out a generator is provided which is comparatively easy to clean and to repair. The flue structure C can be easily and quickly removed as a whole for the purpose of putting in new tubes or stopping 105 leaks. Said flue structure being a considerable distance above the bottom of the boiler is out of the way of the ordinary accumulation of mud, which settles on the bottom of said boiler and may be removed through 110 an aperture left for the purpose and covered by a plate a^3 .

Having thus fully described my said invention, what I claim as new and desire to secure by Letters Patent, is:

1. A steam generator comprising an outer shell, an inner shell providing a flue, a plurality of water tubes passing through said flue and secured thereto, and certain of said tubes connected in series and communicating 120 with the water supply providing a feed water heater, substantially as set forth.

2. A steam generator comprising an outer shell, an inner shell disposed horizontally in the outer shell and providing a combustion 125 chamber and a flue, a plurality of open ended water tubes passing transversely through said flue for a portion of its length,

and a series of connected water tubes passing transversely through the flue and communicating with the source of water supply and the interior of said outer shell, substantially as set forth.

In witness whereof, I have hereunto set my hand and seal at Washington, Dis-

trict of Columbia, this 12th day of July, A. D. nineteen hundred and eleven.

WILLIAM T. HARRIS. [L.S.]
